CLAIM

The ornamental design for a label with a touch graphic, as shown and described.

DESCRIPTION

A portion of the disclosure of this patent document contains material to which a claim for copyright is made. The copyright owner has no objection to the reproduction of the patent document or the patent disclosure, as it appears in the U.S. Patent Office records, but reserves all other copyright rights whatsoever.

The FIGURE is a top plan view of a label with a touch graphic. No claim is made to a thickness of the label.

The broken line of the label and the other broken lines in the drawings form no part of the claimed design.
